SEAM BASTER

Robert Hughes, Woodside, N. Y.

Application March 19, 1952, Serial No. 277,391

3 Claims. (Cl. 33—2)

1

Generically, the invention relates to a seam baster.

Heretofore basting a seam in a garment has been accomplished in one of several ways. For example, it has been done by sewing the two layers of fabric together by spaced and relatively loose stitches—then the superposed layers of fabric are run through the sewing machine to sew the seam along the line of the loose stitches, and the latter pulled out after sewing. This was a more or less "hit" or "miss" method, the operator relying on "eye" to sew the fabric along the desired line.

Another method employed the pinning of the layers of fabric at spaced intervals—the pins inserted at right angles to the line along which the seam would be stitched as the present day sewing machine is equipped to sew over the pins without disturbance of the sewing operation. This pinning was also subject to inherent drawbacks, i. e., the fingers of the worker would be frequently stuck by the pins. It was also "hit or miss" unless a ruler were used each time a pin was inserted.

I have devised a seam baster which has for one of its objects the provision of a device which may be employed to accurately and expeditiously baste seams without the risk of sticking the fingers, and which will measure the line along which the seam is to be stitched with exactitude.

Another object is a seam baster which will hold the superposed layers of cloth while the line of the seam is being sewn by successive pinning of the fabric together.

Another object is the provision of a seam baster which can be easily and economically manufactured of readily available materials, for example—plastics or other man-made materials having the desired rigidity. These and other objects will be apparent after a perusal of the specification and drawings.

Briefly described, the invention comprises a pair of cooperating and oppositely disposed clamping jaws having fixed at their inner terminal ends a pair of gripping members adaptable to grip superposed layers of cloth, with longitudinally disposed bifurcations in the jaws adapted to receive and guide a pin through the crimped portions of the layer of cloth.

In the drawings:

Figure 1 is a perspective view of the seam baster shown in use.

Figure 2 is a cross-section along line 2—2 of Figure 1.

Figure 3 is a section taken along lines 3—3 of Figure 1.

2

Figure 4 is an exploded perspective view of the seam baster.

Figure 5 is a fragmentary perspective view of a modification.

Figure 6 is a cross-sectional view of the same modification, through line 6—6 of Figure 5.

Figure 7 is a fragmentary perspective view, of another modification.

Figure 8—a cross-section along lines 8—8 of Figure 7.

Figure 9 illustrates a fragmentary perspective view of a modification used in upholstering.

Figure 10—a cross-section of Figure 9 through lines 10—10.

Figure 11—a top plan view of the seam baster shown in use.

With reference to the drawings, numeral 5 denotes the seam baster generally, comprising jaws 6 and 7, each having a longitudinally disposed channel therethrough, as at 8 and 9, said channel provided for facile insertion of spring 10, which exerts a clamping action on members 6 and 7. Cooperating recess 11 and nubs 12 prevent displacement of jaws 6 and 7 when the baster is used.

Integral with jaws 6, 7 and oppositely disposed thereto are handles 13 and 14 which can be grasped manually for manipulation of the seam baster 5.

On the inner, confronting opposing faces of jaws 6, 7 are formed respectively transversely disposed tooth 15 adapted to nest opposing tooth 16 when the handles 13, 14 are not manually closed, and the baster is in gripping position, as illustrated in Figures 1, 2, 3.

Teeth 15 and 16 are bifurcated as at 17, 18, so that when the baster is used, for example, in Figure 1, a pin, as indicated by the letter P, can be inserted transversely through the closed jaws and pin superposed layers of cloth together.

Along the opposite edges of jaw 7, which is preferably wider than jaw 6, I provide measurement indicia 19, enabling both right- and left-handed persons to use the seam baster.

In use, as illustrated by Figures 1, 2, 3 and 4, the operator, home user, or other user, clamps the jaws 6, 7 on opposite sides of the layers of the cloth along which the desired seam is to be basted inwardly of the edges the measured distance, and thrusts the pin through end of the baster so that it pierces the layers of cloth as best shown in Figure 3. This operation is repeated at spaced intervals until the seam is the desired distance. The baster is characterized by

ease of operation, there are no parts which can conceivably become inoperable and the seam is

3

basted without danger of pricking the fingers, or any "hit or miss" measurements. The seam can then be sewn on the machine following the line at the point of entrance or exit of the pins through the cloth.

The modification illustrated on Figures 9 and 10 discloses a seam baster being adaptable for use in upholstering, with the jaws 6, 7 having the cooperating teeth 20, 21 bifurcated transversely to permit the pin to be thrust into the side of the baster rather than into the end. The modification depicted in Figures 5 and 6 shows multi-pronged bifurcated teeth 22, 23 in contradistinction to the arcuate-like teeth 15, 16 shown in Figures 1, 2, 3. The further modification of Figures 7 and 8 shows another form of cooperating teeth 23, 25, which may be employed.

In conclusion, the seam baster is a boon to dressmakers as the present day teaching advises the use of pinning instead of basting with stitches since most of the newer sewing machines are equipped to sew over pins and a new footing can be purchased for the older machines.

I reserve the right to make such changes or modifications as may come within the scope of the appended claims.

I claim:

1. A seam baster for clamping upon superimposed layers of cloth, comprising a pair of clamping jaws, spring hinged to each other at their medial portions and provided with handles positioned at the ends thereof opposite the jaws for manual manipulation, one of the jaws having a tooth on its inner face at the outer end thereof, said tooth being bifurcated and provided with a transverse, dome shaped recess with the bifurcations positioned lengthwise of the jaws and in each of the opposite ends, the other jaw also having a bifurcated tooth on its inner face at the outer end thereof; such tooth having a transverse groove facing the bifurcations of the first mentioned tooth and said second mentioned tooth being complementally dome shaped to be received by the recess of the other tooth, the depth of the recess and bifurcations in the first named tooth and the height of the second named tooth and the depth of the transverse groove being sufficient so that when the seam baster is clamped upon superposed layers of cloth, a pin may be received and thrust lengthwise of the jaw through the teeth and through the layers of cloth and held between the teeth, the pin guided by the mating bifurcations and grooves.

superimposed layers of cloth, a pin may be received and thrust lengthwise of the jaw through the layers of cloth held between the teeth guided by the mating bifurcations and grooves.

2. A seam baster as described in claim 1 wherein in one jaw is of uniform greater width than the other and measurement indicia are provided along the extending edges of the jaw of greater width whereby the depth of the seam to be basted may be measured upon clamping the seam baster upon superposed layers of cloth.

3. A seam baster for clamping upon superposed layers of cloth comprising a pair of clamping jaws, spring hinged to each other at their medial portions and provided with handles positioned at the ends thereof opposite the jaws for manual manipulation, one of the jaws having a tooth on its inner face at the outer end thereof, said tooth being bifurcated and provided with a longitudinally extending dome shaped recess with the bifurcations positioned crosswise of the jaws and in each of its opposite ends, the other jaw also having a bifurcated tooth on its inner face at the outer end thereof, said tooth having a longitudinally extending groove mating the bifurcations of the first mentioned tooth and said second mentioned tooth being complementally dome shaped to be received by the recess of the other tooth, the depth of the recess and bifurcations in the first named tooth and the height of the second named tooth and the depth of the transverse groove being sufficient so that when the seam baster is clamped upon superposed layers of cloth, a pin may be received and thrust lengthwise of the jaw through the teeth and through the layers of cloth and held between the teeth, the pin guided by the mating bifurcations and grooves.
